UNITED STATES PATENT OFFICE.

EMIL G. JOHANSON, OF CHICAGO, ILLINOIS.

TIMING DEVICE.

Application filed July 15, 1918. Serial No. 245,037.

To all whom it may concern:

Be it known that I, EMIL G. JOHANSON, citizen of the United States, residing at Chicago, in the county of Cook and State 5 of Illinois, have invented a certain new and useful Improvement in Timing Devices, of which the following is a full, clear, concise, and exact description.

My invention relates to timing devices for 10 indicating the time at which moving objects are stopped or checked or whose motion is otherwise affected and includes mechanism governed by such an object that arrests the 15 operation of such timing device when such object is stopped or has its motion otherwise affected.

In the preferred embodiment of the invention the operation of the timing device is 20 automatically resumed when the normal motion or activity of the object is restored, there preferably being speed accelerating gearing for bringing the time indicating element to correct time indicating position when the timing device is permitted to resume 25 operation so that when the object is next stopped or has its motion otherwise affected the time of its occurrence will again be indicated. In conjunction with such a timing device there is desirably employed 30 a constantly operating timing element which is not operatively influenced by said object so that the time during which the object has been stopped or has its motion otherwise affected may readily be calculated 35 but the invention is not to be limited to its association with such a constantly operating timing element.

Timing devices of my invention are of 40 particular service upon automobiles in those localities which permit automobiles to park only for limited periods of time. A police officer or another in authority, by noting the position of the pointer or index (which may be an extra hour hand) of such a device 45 upon an automobile, would be informed of the time that such automobile came to rest and by comparing the time noted by such hour hand or pointer with the time indicated by his own watch or with the time 50 indicated by the constantly operating clock, if such is employed in conjunction with this hour hand, will readily determine the period of time that the automobile has been at its station. The invention, however, is not 55 to be limited to any particular use to which it may be put.

I will explain my invention more fully by reference to the accompanying drawings showing the preferred embodiment thereof and in which Fig. 1 is a face view illustrating a clock of my invention with the extra hour hand in synchronism with the main hour hand of the clock, this being the condition when an automobile equipped with the device is in travel; Fig. 2 indicates the 60 extra hour hand in an arrested position which would be the condition when the automobile is at rest; Fig. 3 is a view in elevation, partially in section, illustrating the preferred form of mechanism of my invention; Fig. 4 is a view taken on line 4—4 65 of Fig. 5, this figure illustrating a speedometer collocated with the clock of my invention upon the dash board of an automobile; and Fig. 5 is a view on line 5—5 of 70 Fig. 4.

Like parts are indicated by similar characters of reference throughout the different figures.

The object shown in the drawings which 80 is to influence the time indicating mechanism of my invention is a bevel gear 1 upon one end of a flexible shaft 2 on whose other end there is a spur pinion 3. This pinion is in mesh with a spur wheel 4 that 85 may be driven, for example, by motion transmitting mechanism interposed between this gear and one of the propelling vehicle wheels of an automobile. This motion transmitting mechanism includes a flexible 90 shaft 5 that extends to motion transmitting gearing located at and operated by said steering vehicle wheel, the arrangement being such as is commonly found where 95 speedometers are employed. The shaft 5 has a square bore which receives the square end of the shaft 6. The other end of the shaft 6 has a square bore which receives the square end of a shaft 7 that is operatively connected with a speedometer 8 which 100 is well known by those skilled in the art. The shaft 5, which hitherto operated the speedometer, now also operates the motor transmitting elements 1, 2, 3 and 4. The shaft casing 9 is coupled with the gear casing 10 that encloses the gear elements 3 and 4 and affords bearings for these gear elements. This gear casing 10 is also coupled with the casing of the speedometer. The bevel gear 1 is in mesh with a bevel gear 11 105 which is provided upon the shaft 13. This shaft turns in a bearing 14 carried by a 110

bracket structure 15 that is secured to the rear side of a clock casing 16. The clock and the speedometer may be closely collocated upon the dash board 17 of an automobile. The hub of the gear wheel 11 engages one end of the bearing 14 and a collar 18 engages the other end of the bearing and as both hub and collar are fixed upon the shaft 13, this shaft is prevented from having endwise movement. A sleeve 19 surrounds and is movable longitudinally upon the shaft 13. The sleeve carries a collar 20 fixed with respect thereto. Leaf springs 21 are anchored at their ends to the collars 18 and 20. These springs carry centrifugal weights 22. Whenever the automobile is traveling it will impart motion to the shaft 13 through the motion transmitting mechanism described and thereby cause the weights 22 to swing outwardly by centrifugal force. As the collar 18 will not change its zone of rotation the sleeve 19 and the collar 20 will be moved toward the collar 18. When the automobile is at rest the springs 21 will move the sleeve 19 and collar 20 away from the collar 18. A coil spring 23 may be employed to supplement the action of the springs 21.

The index or pointer 24 (preferably in the form of an extra hour hand supplied to a clock which, in the main, is of common make) is fixed upon one end of a longitudinally movable shaft 25 which is aligned with the shaft 13. A brake member 26 is secured to the clock casing 16, the shaft 25 passing freely through this brake member. The brake member 27, which is complementary to the brake member 26, is fixed upon the shaft 25 so as to turn therewith and to accompany this shaft in its longitudinal movements. Gearing for coupling the shafts 13 and 25 is inclusive of a smooth cone pinion 28 fixed upon the sleeve 19 and a corresponding internal cone pinion 29 fixed upon the shaft 25. When the automobile is at rest the sleeve 19 will be moved furthest from the collar 18 and will carry with it the cone pinion 28 (whose plane of rotation is shiftable toward and from the collar 18 because of the fixture of this cone pinion upon the sleeve 19) to separate said pinion from engagement with the internal pinion 29. The pinion 28 has an axial projection 30 which is in alignment with the shaft 25 and engages this shaft when the pinion 28 is moved out of engagement with the pinion 29, a result which occurs, as is understood, when the automobile is at rest. The springs 21 and 23 not only serve to separate the gear elements 28 and 29 but also have sufficient force to move the shaft 25 longitudinally of itself, through the intermediation of the axial projection 30, to effect braking engagement of the brake element 27 with the brake element 26 to prevent the shaft 25 from turn-

ing whereby the index or pointer 24 is held in the place it occupies when the automobile is brought to rest (Fig. 5). This pointer is desirably in the form of an extra hour hand that is mounted to turn over the face 70 of a clock dial 31. The pointer is caused to turn by means of any suitable motor such as a spring or clock motor.

The motor illustrated includes an operating spring 32 secured at one end to a stationary shaft 33 and at its other end to a spur gear wheel 34 which is in mesh with a spur pinion 35 co-axial with the shaft 25 and fixed upon a sleeve 36 that surrounds this shaft. A pinion 37 is also fixed upon the sleeve 36. A spur gear wheel 38 is in mesh with pinion 37 and another spur gear wheel 39, similar to gear wheel 38, is co-axial with respect thereto and is in fixed relation therewith. The wheel 39 is in mesh with a pinion 40 that is fixed upon a sleeve 41 to which a minute hand 42 is secured. A pinion 43, fixed with respect to and co-axial with the wheels 38 and 39, is in mesh with a spur gear 44. This spur gear 44 is fixed 85 with respect to a sleeve 36¹ free to turn with respect to the shaft 25 upon which it is journaled. This sleeve 36¹ carries an hour hand 45 that co-operates with the minute hand 42 to produce a clock which constantly operates when its spring 34 is wound, these hands 42 and 45 sweeping over a clock dial 31. Other gearing illustrated in Figs. 4 and 5 is employed to complete the clock mechanism and as such is well known it will not be 100 described.

In addition to carrying the hour hand 45, the sleeve 36¹ also carries one member 46 of a clutch, this member thus operating in synchronism with the motor, that is, this clutch member has a speed of rotation about the axis of the shaft 25 which bears a constant ratio to each of the other turning parts of the clock train. A clutch member 47 is formed in one integral structure with the index or pointer 24 of the timing device of my invention. The clutch member 46 is desirably in the nature of a lug moving with the hour hand 45. When the automobile has stopped the springs 21 and 23 will, through the thrusting engagement of the cone 28 with the shaft 25, force outward movement of the shaft 25 to separate the clutch member 27 from the clutch member 46, allowing the latter clutch member and the hour hand carrying it to continue their synchronous speed and at the same time permitting the added hour hand or index 24 to remain at rest, a result which is assured by the engagement of the brake member 27 with the brake member 26 that then occurs. As is understood, the gear elements 28 and 29 are separated when the index 24 is held from rotation, that is, when the automobile is at rest, but when the automobile is in travel these gear ele- 120

ments will be engaged to effect a longitudinal movement of the shaft 25 toward the collar 18, a motion which separates the brake member 27 from the brake member 26 and which moves the hour hand 24 inwardly. When the clutch member 47 has been brought into register with the clutch member 46 it will engage the same so that the clock motor will now not only operate the usual clock mechanism but will also operate the extra hand 24 in synchronism with the hour hand 45. Figs. 1 and 3 show the two hour hands in synchronism, a condition which prevails when the automobile is in travel and Figs. 2 and 5 show a condition when the automobile is at rest, Fig. 2 indicating that the automobile has been at rest two hours. The index or pointer 24, when the clutch members 46 and 47 are coupled, moves at an hourly rate which permits the comparatively rapid operating gearing 28, 29 to move the index 24 to a position in which the clutch members 46 and 47 are engaged thereby to enable the index 24 to operate in synchronism with the motor. The gears 28, 29 thus constitute motion accelerating gearing which is controlled by the automobile whose stoppage is to be timed, there being slippage between these gears when the motor drives index 24.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A timing device including an index; a motor for operating the index; and a clutch operatively connecting the motor with the index; in combination with a governor in actuating relation to the clutch to connect the motor with and disconnect it from the index.

2. A timing device including an index; a motor for operating the index; and a clutch operatively connecting the motor with the

index; in combination with a governor in actuating relation to the clutch to connect the motor with and disconnect it from the index; and a brake to hold the index when disconnected from the motor, said brake being operatively connected with the governor to be released thereby when the clutch is actuated to connect the index and motor.

3. A timing device including an index; a motor for operating the index; and a clutch operatively connecting the motor with the index and having one member moved by the motor and another member moving with the index, in combination with gearing operating upon the index.

4. A timing device including an index; a motor for operating the index; and a clutch operatively connecting the motor with the index and having one member moved by the motor and another member moving with the index, these members of the clutch being engageable when the index is in synchronism with the motor; in combination with motion accelerating gearing for bringing the index into synchronism with the motor; and a governor in actuating relation to the motion accelerating gearing.

5. A timing device including an index; a motor for operating the index; and a clutch operatively connecting the motor with the index; in combination with a governor in actuating relation to the clutch to connect the motor with and disconnect it from the index.

6. A timing device including an index; a motor for operating the index; and a clutch operatively connecting the motor with the index; in combination with a governor in actuating relation to the clutch to connect the motor with and disconnect it from the index; and a brake to hold the index when disconnected from the motor and operatively connected with the governor to be released thereby when the clutch is actuated to connect the index and motor.

In witness whereof, I hereunto subscribe my name this eleventh day of June, A. D., 1918.

EMIL G. JOHANSON.
